EXTENSIBLE-PLUNGER PUMP

Application filed August 10, 1927. Serial No. 211,933.

My invention relates to pumps, and it is an object of my invention to provide a novel pump for use in deep wells.

In pumping deep wells, and particularly oil wells, a reciprocating pump is usually placed in the well at the lower end of a string of pump tubing which extends to the top of the well. The pump has a barrel connected to the tubing and a plunger which is suspended from the lower end of a string of sucker rods extending through the tubing and operated from the top of the well so as to reciprocate the plunger in the barrel. These pumps are necessarily of small diameter and in order to get volume the stroke must be relatively long. It is therefore of vital importance that the internal or wearing surface of the barrel be ground to a high degree of accuracy, so that the plunger will make a fluid-tight fit therein without jamming. The accurate grinding of these long internal surfaces of small diameter is very expensive but previously no pump has been produced which does not require this.

It is an object of my invention to provide a deep well pump in which the ground surfaces required are relatively short, thus greatly decreasing the initial cost of the pump.

The rate of wear between the plunger and barrel of a reciprocating deep well pump measures the life of the pump. In the ordinary pump of this class where a single plunger slides against a single wearing surface of the barrel for the complete length of the stroke, the abrasive effect of sand admitted between the plunger and the barrel is so great that the pump must be frequently raised to the surface of the ground for repairs.

It is a further object of my invention to provide a deep well pump in which a plurality of plungers operate in an equal number of barrels, the length of the stroke of the pump being divided between these plungers so that the abrasive action tending to wear away the sliding surface of each barrel and its plunger is correspondingly decreased.

Further objects and advantages will be made manifest in the following description and in the accompanying drawings in which

a preferred embodiment of my invention is illustrated. In the drawings

Fig. 1 is a vertical sectional view illustrating the upper portion of a deep well pump embodying the features of my invention. 55

Fig. 2 is a vertical sectional view illustrating the lower portion of the same pump.

Fig. 3 is a horizontal sectional view taken on the line 3—3 of Fig. 1.

Fig. 4 is a diagrammatic vertical sectional view illustrating the complete pump shown in Figs. 1 and 2. 60

Fig. 5 is a vertical sectional view diagrammatically illustrating a modified form of pump embodying the features of my invention. 65

Referring to the drawings, one embodiment of my invention comprises a deep well pump 10 which includes a tubular shell 11 connected by an upper collar 12 to the lower end of a string of pump tubing 13 and by a lower collar 14 to a well-oil inlet pipe 15. The oil pump 10 is adapted to be disposed in the bottom of a deep well, the pump tubing 13 extending upwardly to the top of the well. The upper collar 12 has a tapering seat 16, the lower end of which has substantially the same diameter as the shell 11 and the upper end of which has substantially the same diameter as the pump tubing 13. 70

The lower collar 14 has a tapered seat 17 with which the body 18 of a standing valve 19 is adapted to make a sealing fit so as to close the lower end of a chamber 20, provided within the shell 11, against downward movement of fluid therefrom. 80

Extending downward from the top of the well through the pump tubing 13 is a string of sucker rods (not shown), the lower end of which is threadedly connected to a threaded pin 25 of a rod connection 26. The rod connection 26 has a central cavity 27 which is threaded at its lower end, from the upper end of which radial holes 28 communicate with the interior of the tubing 13. 90

Threadedly received in the lower end of the cavity 27 and locked in place by a lock-nut 30 is the upper end of a hanging tube 31. The hanging tube 31 extends downward through the collar 12 into the pump chamber 100

20. The lower end of the hanging tube 31 is threaded externally and an internally and externally threaded nipple 32 of a working valve 33 is screwed upon the lower end of 5 the hanging tube 31. Having its lower end internally threaded so as to tightly screw over the nipple 32 is a tubular cylinder 36. Threadedly received into the upper end of the cylinder 36 so as to provide an annular 10 shoulder 37 projecting inward from this cylinder is a nut 38. Disposed about the hanging tube 31 so as to project downward between the nut 38 and the hanging tube 31 is a piston tube 40 of an intermediate tubular member 41. Screwed upon the lower end of the tube 40 is an annular piston 42 which is provided with annular packing rings 43 to make a fluid-tight fit with the inner surface of the cylinder 36. The tube 40 and 20 the piston 42 make a loose sliding fit with the hanging tube 31.

The intermediate member 41 includes a tubular cylinder 44 which is integrally connected with the upper end of the tube 40 and 25 is of substantially the same diameter and length as the cylinder 36. The upper end of the cylinder 44 is internally threaded and a nut 46 is screwed therein to provide an annular shoulder 47 extending inward from the 30 cylinder 44.

Disposed about the hanging tube 31 and making a loose fit therewith is a plug member 50 having a tapering outer surface 51 on the upper portion thereof which is adapted to 35 fit the tapering seat 16 of the collar 12. Provided about the lower portion of the plug 50 are a series of packing rings 52 which engage the inner surface of the upper end of the tubular shell 11 so as to make a fluid- 40 tight fit therewith. Extending downward from the lower end of the plug 50 is a tube neck 55, the lower portion of which is disposed between the nut 46 and the hanging tube 31. The lower end of the neck 55 is externally threaded and a piston 57 is screwed 45 thereon, the piston 57 having annular packing rings 58 which make a fluid-tight fit with the inner surface of the tubular cylinder 44. The plug 50, the neck 55, and the piston 57 50 make a loose sliding fit upon the hanging tube 31.

In Fig. 4 the pump 10 is illustrated to show the cylinder 44 of the intermediate member 41 receiving a plunger 60 of a second intermediate member 61 identical with the member 41, instead of receiving the piston 57 of the plug 50, as shown in Fig. 1. The inclusion of the second intermediate member 61 in Fig. 4 is merely to illustrate 55 the possibility of having any number of intermediate members 41 assembled in end-to-end relation upon the hanging tube 31 provided that the hanging tube 31 and the shell 11 be made of sufficient length to accommodate these intermediate tubular members.

Cooperating with the upper piston 57 which has a fixed relation upon the plug 50 and the lower cylinder 36 which is carried by the lower end of the hanging tube 31, these intermediate tubular members form a telescopic envelope 65 which operates as follows.

After the pump tubing 13 has been installed in the well with the collars 12 and 14 and the shell 11 assembled on the lower end thereof, the standing valve 19 is then lowered into place. The remaining parts of the pump 10, assembled as they are upon the hanging tube 31, are now lowered into the tube 13 suspended upon the lower end of the string of sucker rods previously mentioned. While being lowered, the tubular members telescopically mounted upon the hanging tube 31 are in telescoped or collapsed position. When the plug 50 fits upon the seat 16 so that the packing rings 52 make a fluid-tight fit with the upper end of the shell 11, the sinking of the hanging tube 31 farther into the chamber 20 causes an extension of the envelope 65. Fig. 4 shows this envelope 80 almost completely extended.

The pump 10 is now operated by reciprocation of the hanging tube 31 by the string of sucker rods to which it is connected. As the hanging tube 31 moves upward, the working valve 33 closes, causing the standing valve 19 to open and admit well fluid into the chamber 20. When the hanging tube 31 has practically collapsed the envelope 65 on its up stroke and has started its down stroke, the standing valve 19 is closed and the working valve 33 opens to cause the fluid admitted to the chamber 20 to pass upward through the working valve 33.

The envelope 65 maintains a fluid-tight connection between the plug 50 and the working valve 33 throughout the length of the stroke of the hanging tube 31 without any two wearing parts sliding together over a corresponding distance. In fact, the working stroke of the pump is divided between the pistons 42, 57 and 60 so that each moves in its corresponding cylinder only one-third the distance of the entire stroke of the pump. This results in a much lower abrasive effect upon the cylinders so that the life of the wearing surfaces of these cylinders is much longer than the life of the cylinder of a single plunger pump having the same stroke as the pump 10.

There is a great demand for pumps having longer strokes than those now in use but experimental pumps designed to fill this demand have shown that the abrasive effect of the piston upon the cylinder is so great that a single plunger pump with a barrel of considerable length is impractical. By the use of my invention pumps of any desired stroke may be made without increasing the abrasive effect between the sliding parts

thereof. Likewise it is to be noted that there are very few ground surfaces required on the parts of the pump 10 and that where these are required they are very short in length. 5 Thus the longest ground surface required in the pump 10 is the internal surface of each of the cylinders making up the envelope 65 which, as above noted, need be only a third as long as the barrel of a single plunger pump 10 having the same length of stroke as the pump 10.

Fig. 5 shows a modified form of pump 70 embodying my invention. In the pump 70 a pump tubing 71 has a seat 72 formed therein upon which a standing valve 73 is adapted to rest. Extending upward from the standing valve 73 is a tubular piston member 74 which remains stationary during the operation of the pump. Formed upon the upper 20 end of the piston member 74 is a piston 75 which works in the cylinder 76 of an intermediate member 77. Provided on the upper end of the intermediate member 77 is a plunger 78 which is adapted to work in a cylinder 79. The cylinder 79 has a working 25 valve 80 provided to control an opening therefrom into the interior of the tubing 71. The cage of the working valve 80 is connected to a string of sucker rods 81 by which a telescopic envelope 82, formed by the cylinder 79, the plunger 74 and the intermediate member 77 may be extended by drawing upward on the cylinder 79. As the envelope 82 is extended, the standing valve 73 is opened to 30 admit oil into a chamber 83 formed within the envelope 82. As the cylinder 79 is allowed to drop so as to collapse the envelope 82, the standing valve 73 closes and the oil 35 trapped in the chamber 83 opens the working valve 80 and passes out into the interior of 40 the pump tubing 71.

I claim as my invention:

1. In a deep well pump the combination of: a plurality of adjacent pairs of tubular members telescopically connected together in series to form a continuous chamber therein; means for fixing one end of said series; means for moving the other end of said series to telescopically lengthen or shorten said series; and valve means confining the flow of fluid through said chamber to a flow in a single direction.

2. In a deep well pump, the combination of: a plurality of longitudinally adjacent 55 pairs of telescopically conengaging tubular members connected together in series to form an expandible and contractile pumping unit; means for fixing one terminal member of said series; means for moving the opposite terminal member of said series to lengthen or shorten said unit; and means for insuring a unidirectional flow of pumped fluid through said unit.

3. In a deep well pump the combination 65 of: a plurality of adjacent pairs of tubular

members telescopically connected together in series to form a continuous chamber, one end of said series being fixed; means for fixing one end of said series; a standing valve for admitting liquid into said chamber; means for moving the other end of said series to lengthen or shorten said series; a working valve connected with said chamber through one of the tubular members of said series; and means for reciprocating the last mentioned tubular member.

4. In a deep well pump the combination of: a plurality of pairs of tubular members telescopically connected together in series to form a continuous chamber therein, one end of said series being fixed; means for moving the other end of said series to lengthen or shorten said series; and valve means confining the flow of liquid through said chamber to a flow in a single direction.

5. In a deep well pump the combination of: a plurality of pairs of tubular members telescopically connected together in series to form a continuous chamber therein; means for fixing one end of said series; means for moving the other end of said series to lengthen or shorten said chamber; and a valve confining the flow of liquid through said chamber to a flow in a single direction.

6. In a deep well pump the combination of: a plurality of adjacent pairs of tubular members telescopically connected together in series to form a continuous chamber therein; a tubular member to which one end of said series is fixed; means for moving the other end of said series to lengthen or shorten said series; and means for confining the flow of liquid through said chamber to a flow in a single direction.

7. In a deep well pump the combination of: a series of tubular members serially and telescopically connected together to form a continuous chamber therein; means for fixing one end of said series; means for lengthening or shortening said series; and a valve in the fixed end of said series adapted to confine the flow of liquid through said chamber to a flow in a single direction.

In testimony whereof, I have hereunto set my hand at Los Angeles, California, this 5th day of August, 1927.

EDGAR W. PATTERSON.
